UNITED STATES PATENT OFFICE.

ERNEST BRIGHT ROLLASON, OF SYDNEY, NEW SOUTH WALES, AUSTRALIA.

ONE HOOKED MEMBER FOR ORNAMENTAL HAIR-COMBS AND THE LIKE.

1,260,815.

Specification of Letters Patent. Patented Mar. 26, 1918.

Application filed June 26, 1916. Serial No. 105,853.

To all whom it may concern:

Be it known that I, ERNEST BRIGHT ROLLASON, subject of the King of Great Britain and Ireland, residing at 121 Castlereagh street, Sydney, New South Wales, Australia, have invented new and useful Improvements in One Hooked Members for Ornamental Hair-Combs and the like, of which the following is a specification.

10 The invention consists in returning at an angle, or making a hook to, one of the teeth, preferably the longest or one of the longest teeth, of the comb. If more than one tooth were hooked, the advantage derived from 15 hooking one tooth would be neutralized.

In the accompanying drawing:—

Figure 1, is a perspective view of an ornamental hair comb having five teeth, the central one being the longest, and is therefore hooked.

Fig. 2, is a perspective view of an ornamental hair comb having but two teeth, one of which is longer than the other; the longer tooth is shown with the hook.

25 Referring to the drawing by numerals, and particularly to Fig. 1, the numeral 1 designates the body of the comb, which has a long tooth 2 and a number of shorter teeth

3. The extremity of tooth 3 is bent laterally into a hook 4. Owing to the provision 30 of the hook on this particular tooth, it may be engaged in the hair of the wearer effectively and still may be extracted without interference by the other teeth.

In Fig. 2, the body 1' is represented as 35 having a long tooth 2', but only one short tooth 3'. The hook 4' is formed on the extremity of the long tooth in the same manner as in the modification of Fig. 1.

I claim—

40 An ornamental hair comb comprising a body, a plurality of teeth of various lengths extending from said body in the same general direction, the longer of said teeth being located centrally with respect to the other 45 teeth and having the free end thereof formed with a hook, said hook being disposed in the same plane as said body.

In testimony whereof I have signed my name to this specification in the presence of 50 two subscribing witnesses.

ERNEST BRIGHT ROLLASON.

Witnesses:

B. MASSEY,
E. HYDE.
